Inventor
John F. Appleby

UNITED STATES PATENT OFFICE.

JOHN F. APPLEBY, OF CHICAGO, ILLINOIS, ASSIGNOR TO DEERING HARVESTER COMPANY, OF CHICAGO, ILLINOIS.

GRAIN-HARVESTER.

SPECIFICATION forming part of Letters Patent No. 720,096, dated February 10, 1903.

Application filed May 17, 1902. Serial No. 107,873. (No model.)

To all whom it may concern:

Be it known that I, JOHN F. APPLEBY, of Chicago, in the county of Cook and State of Illinois, have invented a certain new and 5 useful Improvement in Grain-Harvesters, of which the following is a specification.

This improvement relates more particularly to that class of grain-harvesters known as "headers," its object being to provide 10 more suitable means than heretofore in use for supporting and adjusting the grain-elevator at any desired height, and particularly to facilitate the raising and lowering of the grain-elevator in order to avoid collision with 15 the "barge" that receives the grain when it is driven alongside the elevator. This object is attained by the use of a counterpoising-spring to in part counteract the weight of the elevator.

20 In the accompanying drawings, Figure 1 is a perspective view of a portion of an ordinary Appleby header provided with my improvement; and Fig. 2 is a detail of my improvement, showing how I prefer to support it.

A represents the main frame of the header; B, the axle, which may be sustained in the usual supporting-wheels, the position of the main wheel b' shown only by dotted lines.

30 C is the thrust-tongue, connected at its front end to the axle and other parts of the frame and may be considered as supported on a caster-wheel at its rear end in the usual manner; D, the grain-receiving platform, 35 supported in front of the wheels also in the usual way and provided with suitable levers for adjusting the height of same; and d, the platform-conveyer, which delivers the grain to the endless elevator G and H.

40 E is the cutting apparatus, arranged along the front side of the grain-receiving platform, involving nothing new in its design or means of operation, and hence need not be described.

F represents the vertically-adjustable elevator-frame, inclining upwardly from the delivery end of the platform conveyer and pivotally attached to the frame of the machine. In the frame F are journaled the rollers g g' and h h', over which pass the conveyer-can- 45 vases G and H, g' and h' being broken away 50 with upper portion of frame in Fig. 1.

I is a tackle secured to the upper end of the elevator F. The rope i of the tackle I passes over the blocks i', i², and i³, thence rearward to the customary operator's stand. 55 By means of this tackle the attendant adjusts the height of the elevator. Secured rigidly to a suitable portion of the platform-frame, forward of the axle B and extending upwardly, is the post J, preferably of angle-iron. In addition to supporting the block i³ the post J also forms a support for the bearing k, in which journals the wrist of the bell-crank K. To the upwardly-extending arm 60 of the bell-crank K is linked the elevator F 65 through the rod L, the rod L being attached to F near its upper end by means of an eye-bolt, thus forming a flexible joint.

m is a brace-rod secured to the post J at its upper end and extending downwardly to 70 a suitable point on the grain side of the main frame. Near the foot of the post J is secured an outreaching arm n, or it may be a bent extension of J. Interposed between the horizontal arm of the bell-crank K and the 75 outreaching arm n is the spring M, in the ends of which are screwed the fasteners or nuts m' m², adapted to be received by the spring M. The nuts m' and m² are tapped for rods or bolts. The nut m' receives the 80 rod n', which connects it with the horizontal arm of the bell-crank K, and the nut m² receives the bolt n², which connects the lower end of the spring with the outreaching arm n. The bolt n² is provided with a long threaded portion at its upper end, which thus permits of an adjustment of the tension of the spring by turning the said bolt n². 85

By the means described, whereby most of the weight of the elevator is supported by the 90 spring M through the instrumentality of the bell-crank K and the rod L, it is seen that my improvement operates to facilitate the manipulation of the hinged elevator F.

Having thus described my invention, what 95 I claim, and desire to secure by Letters Patent, is—

1. In a harvesting-machine, a grain-receiving platform adjustable in height, a grain-elevator pivotally secured thereto at its 100 lower end, means for adjusting the height of the said grain-receiving platform, a counter-

balancing-spring adapted to support and counterpoise the free end of the said grain-elevator, and means, independent of the said means for adjusting the height of the said 5 grain-receiving platform, for raising and lowering the said grain-elevator at will, substantially as described.

2. In a harvesting-machine, the combination of a main frame, a vertically-adjustable 10 elevator F, pivotally secured to the main frame, a post J secured to the main frame and extending upwardly, a tackle suitably

arranged to raise and lower said elevator, a bell-crank K pivotally connected to said post J, with connections between the vertical arm of said bell-crank K and the elevator F, and a spring connection between the horizontal arm of the bell-crank K and the frame A of the machine, all combined substantially as described. 15

JOHN F. APPLEBY.

In presence of—

EDWARD R. BARRETT,
J. C. WARNER.
